UNITED STATES PATENT OFFICE.

FREDERICK W. FULLERTON, OF ST. PAUL, MINNESOTA.

SWITCH FOR NEWSPAPER-CONVEYERS.

1,262,767.

Specification of Letters Patent. Patented Apr. 16, 1918.

Application filed April 21, 1917. Serial No. 163,689.

To all whom it may concern:

Be it known that I, FREDERICK W. FULLERTON, a citizen of the United States, residing at St. Paul, in the county of Ramsey 5 and State of Minnesota, have invented new and useful Improvements in Switches for Newspaper-Conveyers, of which the following is a specification.

My invention relates to an improved 10 switch for use on newspaper conveyers, and is particularly, though not exclusively, adapted for use on conveyers of the type shown in United States Letters Patent No. 1,138,609, issued to me on the 4th day of 15 May, 1915.

The object of my invention is to provide a simple and efficient switch adapted to facilitate a change of direction in the movement 20 of the papers when it is desired to transfer them from a vertical to a horizontal plane, or vice versa.

In the drawings, Figure 1 is a plan of my improved switch; Fig. 2 is a section on the line 2—2 of Fig. 1; Fig. 3 is a detail of the 25 transfer sheaves and their mountings partly in central section; Fig. 4 is a perspective view of one of the eccentric bushings of the transfer sheaves; Fig. 5 is a detail showing the means for shifting the position of the 30 guide fingers; and Fig. 6 is a sectional detail on the line 6—6 of Fig. 5.

My switch is applicable to any system of newspaper conveyers consisting of a plurality of pulleys upon which belts are arranged 35 to receive newspapers from a printing press and transfer them automatically in continuous succession or slightly overlapped through any convenient course within the available quarters of the printing 40 establishment to a delivery table where the newspapers are ordinarily stacked and counted. Such delivery table may be located above or below or on the same floor, at a considerable distance from the printing 45 press. In such conveyers the papers when moving in a horizontal plane ordinarily rest upon a single conveyer, but when the line of travel is up or down the papers are carried by friction between two closely adjacent and 50 substantially parallel runs of belts.

In the drawings, the numerals 9 and 10 indicate conveyer pulleys and 11 and 11^a carrier belts constructed, arranged, and operated in the usual way. To switch or 55 change the direction of travel of the papers from a vertical line of such carriers to a

horizontal line, or the reverse, I provide the following mechanism: Adjacent to the turning point is a horizontal shaft 12 journaled at each end in a suitable frame 13. 60 The purpose of this shaft is to form a support for a plurality of transfer sheaves 14 and 15 arranged in pairs and revoluble upon bushings 16 which are eccentrically mounted upon the shaft 12. By reason of such 65 mounting, the sheaves of each pair are offset with respect to each other. The transfer sheaves 14 and 15 of each pair are held side by side by collars or flanges 17 formed on the bushings which are fixed to the shaft 12 70 by means of set screws 18. The transfer sheaves 14 are driven in a clockwise direction by means of the switch belts 19, which extend from said sheaves to the driven pulley 9, and the sheaves 15 are driven in a 75 counter-clockwise direction by the switch belts 19^a from the pulley 10. These switch belts, which also coöperate with parallel belts 11 and 11^a to convey the papers, are disposed in diverging lines of travel and are 80 brought into such parallel alinement with their respective companion belts 11 and 11^a by the oppositely arranged offsets of the sheaves 14 and 15.

To coöperate with the transfer sheaves and 85 their belts, I fix upon the shaft 12, adjacent to each pair of pulleys, a guide finger 20 which may be turned with said shaft into the path of an advancing series of papers, in order to deflect such papers from their former 90 course. This finger in Fig. 2 is illustrated as in position to deflect advancing papers from a vertical to an oblique course, and it is to be understood that when said finger is shifted to the position shown in dotted lines (Fig. 95 2), the papers will continue uninterruptedly in their vertical line of travel. The fingers 20 are shifted into or out of the course of the papers by means of a handle 21 on the end of the shaft 12, and are held in the desired position by means of a stop pin 22 fixed to the knob 23. The pin 22 extends freely through an orifice 24 in the handle 21. A coiled spring 25 placed in the orifice 24 about the pin 22 presses against a fixed 100 washer 26 on the pin 22 and tends to hold the end of the pin in a perforation 27 on the side of the frame 13, from which position it may be withdrawn by a pull on the knob 23, and when the fingers 20 are shifted 105 by the handle 21, the point of the pin enters a second perforation 27^a to hold the fingers

in their new position. It will be observed that in shifting the fingers 20, the angular movement of the shaft 12 is so slight that the offset peripheries of the sheaves 14 and 5 15 are not removed from operative position, nor are the lines of travel of the belts 19 and 19^a, which run over these sheaves, substantially changed.

In operation, when it is desired to change 10 the direction of travel of the newspapers, the operator simply manipulates the knob 23 to move the pin 22 from one perforation to the other, and thus shifts the position of the guide fingers 20 into the path of the 15 papers which are thereby deflected from the path of the belts carried upon one series of offset sheaves to that carried by the other series of offset sheaves, when the diverging switch belts coöperating with the companion parallel belts of the system will grip 20 the papers and transfer them into their new path.

Having described my invention, what I claim as new and desire to protect by Letters 25 Patent is:

1. The combination with a plurality of diverging carrier sections adapted to receive papers from a common source of supply, each section comprising two series of coöperating conveyer belts lying parallel to each other, of a switch comprising a shaft 30 mounted adjacent to the line at which said carrier sections diverge, a series of eccentric bushings mounted in pairs upon said shaft, 35 sheaves revoluble upon each of said bushings, so that the sheaves of each pair are offset with respect to each other, one series of conveyer belts of each carrier section passing over said sheaves and a series of guide 40 fingers mounted upon an adjustable shaft and adapted to divert the papers into either carrier section from said common source of supply.

2. The combination with a plurality of 45 diverging carrier sections adapted to receive papers from a common source of supply, and each section comprising two series of coöperating conveyer belts lying parallel to each other, of a switch comprising a shaft 50 mounted adjacent to the line at which said carrier sections diverge, a series of eccentric bushings mounted in pairs upon said shaft, sheaves revoluble upon each of said bushings so that the sheaves of each pair are offset 55 with respect to each other, one series of conveyer belts of each carrier section passing over said sheaves and also over driven pulleys disposed in different vertical planes, and a series of guide fingers mounted upon an 60 adjustable shaft and adapted to divert the papers into either carrier section from said common source of supply.

3. In a newspaper conveyer, a switch comprising a shaft, a plurality of bushings 65 mounted in pairs upon said shaft, sheaves

severally revoluble upon each of said bushings which are disposed with peripheries oppositely eccentric to the axis of the shaft, conveyer belts passing over each of said sheaves and also over pulleys disposed in 70 different vertical planes, coöperating belts lying parallel to each of said conveyer belts and forming therewith carrier sections, means to normally feed papers to one of said carrier sections, and a series of oscillatory guide fingers mounted upon an adjustable shaft and adapted to divert the papers into the other of said carrier sections. 75

4. In a newspaper conveyer, a plurality of pairs of diverging conveyer belts, the adjacent ends of each pair of said belts being arranged upon sheaves placed side by side and having their peripheries offset with respect to each other, an oscillating guide finger placed adjacent to the converging 80 ends of said belts and adapted to be turned into or out of the line of travel of said belts, means for driving said belts, and coöperating carrier sections arranged in close parallel relation to each of said diverging belts. 85

5. In a newspaper conveyer, a plurality of pairs of diverging conveyer belts, the adjacent ends of each pair of said belts being disposed upon sheaves placed side by side 90 and having their peripheries offset with respect to each other, an oscillating guide finger placed adjacent to the converging ends of said belts, means for holding said finger either in or out of the path of the papers carried by said belts, means for driving said belts, and coöperating carrier sections arranged in close parallel relation to each of said diverging belts. 95

6. In a newspaper conveyer, a switch comprising a horizontal shaft, a plurality of bushings mounted in pairs upon said shaft, sheaves severally revoluble upon each of said bushings which are disposed with peripheries oppositely eccentric to the axis of the shaft and with retaining flanges for the 100 sheaves, means for fixing the bushings on the shaft, conveyer belts passing over each of said sheaves and also over pulleys disposed in different vertical planes, coöperating belts lying parallel to each of said conveyer belts and forming therewith carrier sections, means to feed papers to a line adjacent to said horizontal shaft, and a series of guide fingers mounted upon an adjustable 110 shaft and adapted to divert the papers into either of said carrier sections. 115

7. In a newspaper conveyer, a switch comprising a shaft, a plurality of bushings mounted in pairs upon said shaft, sheaves severally revoluble upon each of said bushings which are disposed with peripheries oppositely eccentric to the axis of the shaft, conveyer belts passing over each of said sheaves and also over pulleys disposed in 125 different vertical planes, coöperating belts 130

- lying parallel to each of said conveyer belts and forming therewith carrier sections, means to feed papers to a line adjacent to said shaft and oscillatory guide fingers 5 mounted upon an adjustable shaft and adapted to divert the papers into either of said carrier sections, and means for holding said fingers either in or out of the path of the advancing papers.
- 10 8. The combination with a main newspaper carrier section, of an auxiliary carrier section diverging therefrom, a shaft mounted adjacent to the line of divergence, eccentric
- sheaves mounted on said shaft, conveyer belts for said sheaves, certain of said belts 15 coöperating with said main carrier section, while others coöperate with said auxiliary carrier section, and oscillatory fingers mounted adjacent to said line of divergence, said fingers being adapted to deflect papers 20 from said main carrier section to said auxiliary carrier section.

Whereof I have hereunto subscribed my name to this specification.

FREDERICK W. FULLERTON.
